BOOKBINDING AND MEANS FOR BINDING BOOKS

Emma Jane Crone, Marathon, Iowa

Application April 19, 1934, Serial No. 721,343

4 Claims. (Cl. 281—23)

This invention relates to bookbinding and has to do with an improved device for fastening the contents of a book in its cover. It may be used either in the original binding of a book or in 5 rebinding when the cover has become detached from the contents.

The invention consists of the following device and the method of its application:

Two layers of suitable binding material with 10 an intervening layer of adhesive-repellent material are stitched together so that one layer of the binding material is adapted to be adhesively fastened to the back and adjacent end papers of the contents of a book, and the other layer of 15 binding material is adapted to be adhesively fastened to the back and adjacent leaves of a book cover, the intervening layer of adhesive-repellent material serving to keep the binding materials from adhering to each other when an adhesive 20 is applied to them, and further serving as a convenience in keeping the adhesive from other undesired places.

The usual commercial devices marketed at the present time, and which have for their purpose 25 the attachment of the contents of a book to its cover, are made of gummed materials, such as tape, book cloth, adhesive paper, or similar materials. Such materials are not recommended by persons familiar with the mending or original 30 binding of books, and who have made actual tests with different materials. Experience has proved that the softer and lighter weight the mending fabrics, the better for the book and the more enduring the results. Because gummed materials 35 are more quickly and easily used, they are often applied without discrimination and frequently result in damage to the book. It is generally accepted that ungummed cloth is more adhesive and flexible, and also less expensive, than the gummed 40 materials commonly in use. However, it has not heretofore been practicable to make such devices from inexpensive ungummed materials, since when an adhesive is applied to such materials it penetrates them and causes the materials to adhere to each other, thus destroying the freedom 45 of the layers of binding material from each other. The use of ungummed materials of a nature which is not penetrable by the adhesive substance to be used is equally impracticable, since the expense 50 of such materials is prohibitive in a device of this nature, if it is to prove a commercial success.

The devices now in common commercial use are made of materials to which an adhesive has been applied and allowed to dry before the various 55 portions of the device are stitched together. Com-

sequently, the adhesive hardens, cracks and deteriorates with time, and when eventually used in bookbinding, the adhesive does not adhere firmly and effectively. Materials thus prepared also have a tendency to curl when used, which is a distinct disadvantage and is not found in my invention.

My invention consists of a novel combination of materials, and a method for their use, which is described by this specification, illustrated by the 10 accompanying drawing, and fully claimed hereinafter. My invention is designed to make possible the use of ungummed materials, especially such as are inexpensive, in the art of bookbinding by means of a device so effective and economical 15 and a method so quick and easy that there will no longer be any inducement to employ inferior gummed materials.

A brief description of the accompanying drawing, in which like numerals of reference indicate 20 like parts in the several figures, follows—

Figure 1 represents the contents of a book ready to be fastened into its cover.

Figure 2 represents a cover ready to receive the contents of a book.

Figure 3 represents an embodiment of my invention in which two parallel lines of stitches are employed.

Figure 4 represents an end view of a book, bound to its cover by means of the embodiment 30 of my invention represented in Figure 3; after the surfaces 24 of the intervening layer of adhesive-repellent material, which may serve but a temporary purpose, have been removed at the 35 rows of stitches.

Figure 5 represents an embodiment of my invention in which a single row of stitches is employed.

Various modifications of my invention and the method of its use, but employing the same 40 basic principles, will be fully described and claimed hereinafter. It is not desired to confine the invention to the exact forms herein shown and described, but to include all such forms as properly come within the scope claimed.

A detailed description of the drawing, the elements of the invention, and the method of its use follows—

In Figure 1, the book leaves 27 have been assembled in stitched signatures with the exposed 50 signatures and stitches showing in the back 28. The edges of the back of the uncovered book contents are represented by 29. The end papers of the uncovered book contents are represented by 30.

This manner of assembling the contents of a book is well known and forms no part of my invention. The contents may be assembled in any other way, and still may be adapted for use with 5 my improved device for binding the uncovered contents into their cover. The scope of my invention is not limited to use with the contents of a book assembled in the manner illustrated by Figure 1.

10 Figure 2 represents a view of a well known form of book cover, commonly known as a "made cover" in contradistinction to a cover built upon the book itself, as is often done with hand made books. In Figure 2, the numeral 31 represents 15 the back of the made cover. The leaves adjacent to the back of the cover are represented by the numeral 32. Those portions of the cover which are to serve as hinges when the contents and the made cover are joined by my invention are represented by 33. The illustration of a made cover is included for the purpose of clarity only, it being representative of the known prior art, and the cover forming no part of my invention. The scope of my invention is not limited to use with 20 25 the form of cover shown in Figure 2, as the cover may be of any type needing to be fastened to the contents.

Figure 3 represents an embodiment of my invention in which two parallel rows of stitches are 30 employed, in conjunction with the other elements of the invention. The numeral 20 represents the wing flaps, and the numeral 21 the back, of that part of my invention which is to be adhesively fastened to the book contents. The numerals 22 35 represent the wing flaps, and the numeral 23 the back, of that part of my invention which is to be adhesively fastened to the made cover. The intervening layer of adhesive-repellent material is represented in its entirety by the numerals 24 40 and the numeral 25, the wing flaps of the adhesive-repellent layer being represented by the numerals 24, and that portion of the adhesive-repellent layer lying between the parallel rows of stitches being represented by the numeral 25. 45 The parallel rows of stitches are represented by the numeral 26.

Figure 4 represents an end view of a covered book, the contents of which have been bound to a made cover by the use of that embodiment of my 50 invention in which two parallel rows of stitches are employed, as illustrated in Figure 3. In Figure 4, the wing flaps 24 of the intervening layer of adhesive-repellent material (as shown in Figure 3) have been removed, while that section of 55 the intervening layer of adhesive-repellent material represented by the numeral 25, and lying between the parallel rows of stitches, remains in its original position. There is no necessity for removing the wing flaps 24 of the intervening 60 layer of adhesive-repellent material after the cover and contents of the book have been joined. They may be allowed to remain if desired.

Figure 5 represents an embodiment of my invention in which a single row of stitches is employed, in conjunction with the other elements of the invention. The numerals in Figure 5 represent the same elements of the invention as are represented by like numerals in Figure 3.

The various parts of the binder, contents, and 70 cover being thus specified, the method of fastening the contents into the cover consists of two simple operations; namely, (1) adhesively fastening the binder to the contents, and (2) adhesively fastening the contents, thus bound, into 75 the cover. This order of procedure need not nec-

essarily be followed, as the binder may well be first fastened to the cover, and then to the contents. The former procedure is probably the more practicable and more easily accomplished. More fully described, the operations follow:

When using that embodiment of my invention shown in Figure 3, a suitable adhesive is applied to the back of the book contents 28, where it is well stippled in, and to the inner surfaces of flaps 20 and 21 of the binder. These surfaces are then firmly applied to the contents, the lines of stitches 26 lying along the edges 29 of the back of the contents, the width between the parallel lines of stitches conforming with the width of the book contents. Thus applied, the surfaces 20 and 21 of the binder are adhesively bound to the end papers 30 and the back 28 of the book contents.

An adhesive is now applied to the outer surfaces of that portion of the binder represented by 22 and 23, and by means of the adhesive these 20 surfaces are fastened respectively to those portions of the cover represented by 32 and 31. The lines of stitches 26 now coincide with the hinge portions 33 of the made cover.

During the operations described, the intervening layer of adhesive-repellent material represented by 24 and 25 has served to prevent the adhesive substance used from penetrating the respective layers of binding material and causing them to adhere together, and has also acted to prevent the adhesive from reaching other undesired places. When the adhesive has dried, the wing surfaces 24 of the intervening layer of adhesive-repellent material, which can easily be torn at the stitches 26, may be removed (as shown in Figure 4), or be allowed to remain in their original position, whichever may be desired.

In this embodiment of my invention, the two layers of binding material, as well as the intervening layer of adhesive-repellent material, may be of any size desired. The width between the parallel rows of stitches may likewise be of any width desired, such width being governed by the width of the contents of the particular book to which the binder is being applied.

When using that embodiment of my invention shown in Figure 5, which is adapted for binding books the backs of which are comparatively thin, or for fastening pamphlets into their covers, or for refastening loose sections in the contents of books, substantially the same operations take place. The surfaces 20 of the binder are adhesively fastened to the end papers of the contents of the book or pamphlet being bound, while the surfaces 22 are adhesively fastened to the cover of the book or pamphlet. The single row of stitches 26, in this embodiment of my invention, lies along the center of the back of the contents thus bound, and along the center of the cover. The function of the intervening layer of adhesive-repellent material 24 is the same in this embodiment of my invention as it is in that embodiment shown in Figure 3.

I have described a novel method and means by which a book may be effectively fastened in its cover through the use of unglued materials, the use of which is made possible by employing a layer of adhesive-repellent material between the two layers of unglued binding materials. If 70 examination of a book that has been bound by my improved binder and method be made, it will be seen that I have inserted between a book and its cover a layer of adhesive-repellent material, such for example as wax paper, the purpose of 75

which is to prevent the adhesion of the separated surfaces at undesired places. By this I prevent much of the undesirable rigidity of the back of the contents, which so often causes a book to break when being opened. In prior art, materials as thin as netting have commonly been glued to the back of the contents of a book, and it has often been the practice to apply on top of the netting a layer of paper which adhered to the glue that had been used when the netting was applied. The effect of this method of preventing the cover from adhering to the contents has been the rigidity and liability to breakage mentioned. My layer of adhesive-repellent material permanently prevents the adherence of these surfaces, even in cases where future dampness might otherwise lead to their adherence, and it consequently retains for the back of the book a flexibility much desired in the construction of books.

20 I claim:

1. As an article of manufacture, a bookbinding device consisting of two layers of binding material and an intervening layer of adhesive-repellent material, fastened together with two parallel rows 25 of stitches, or the like, the stitches being so spaced that one layer of the binding material is adapted to be adhesively fastened to the back and adjacent end papers of the contents of the book and the other layer of the binding material is adapted 30 to be adhesively fastened to the back and adjacent leaves of the cover, the intervening layer of adhesive-repellent material being utilized for the purposes of keeping the two layers of binding material from adhering to each other when the adhesive is applied to them, and of keeping the adhesive 35 from other undesired surfaces.

2. As an article of manufacture, a bookbinding device consisting of two layers of binding material and an intervening layer of adhesive-repellent material fastened together with a single row of 40 stitches, or the like, in such a manner that one layer of the binding material is adapted to be adhesively fastened to the back and adjacent end

papers of the contents and the other layer of the binding material is adapted to be adhesively fastened to the back and adjacent leaves of the cover of a book or pamphlet which is comparatively thin, the intervening layer of adhesive-repellent material being utilized for the purposes of keeping the two layers of binding material from adhering to each other when the adhesive is applied to them, and of keeping the adhesive from other undesired places.

3. In the art of bookbinding, a device consisting of two layers of binding material and an intervening layer of adhesive-repellent material, fastened together in such a manner that one layer of the binding material is adapted to be adhesively 10 fastened to the back and adjacent end papers of the contents of a book and the other layer of the binding material is adapted to be adhesively fastened to the back and adjacent leaves of a book cover, thus adhesively fastening one side of the 15 binder thus formed to the back and adjacent end papers of the contents of the book and adhesively fastening the other side of the binder to the back and adjacent leaves of the cover, the intervening layer of adhesive-repellent material serving to 20 prevent the two layers of binding material separated by it from adhering to each other when the adhesive is applied, and to keep the adhesive from other undesired surfaces.

4. In combination with the contents of a book 30 and the cover thereof, a layer or layers of adhesive-repellent material, stitched or otherwise fastened between the binding materials to be utilized in fastening the contents of the book into its cover through the application of an adhesive to such 35 binding materials, such layer or layers of adhesive-repellent material being utilized for the purpose of preventing the adhesion of the cover and the contents of the book at any other places than those where it has been designed that the cover 40 and the contents of the book shall be fastened together.

EMMA JANE CRONE.
